UNITED STATES PATENT OFFICE.

DANIEL GEORGE MARTENS, OF CHRISTIANIA, NORWAY.

CONSTRUCTION OF SHIPS OR BOATS.

SPECIFICATION forming part of Letters Patent No. 650,333, dated May 22, 1900.

Application filed January 22, 1900. Serial No. 2,411. (No model.)

To all whom it may concern:

Be it known that I, DANIEL GEORGE MARTENS, a subject of the King of Norway and Sweden, and a resident of Christiania, Norway, but at present residing at 12 Montague Place, Russell Square, London, England, have invented certain new and useful Improvements in the Construction of Ships or Boats; and I do hereby declare the following to be a full, clear, and exact description of the invention, such as will enable others skilled in the art to which it appertains to make and use the same.

The object of this invention is to produce a ship or boat so constructed as to be extremely steady and especially adapted for life-saving purposes or for working in heavy seas.

In the accompanying drawings, Figure 1 is an elevation, Fig. 2 a plan, and Fig. 3 a central transverse vertical section, of a boat constructed according to this invention.

In constructing the lines of the boat or ship I form each side thereof with two longitudinal inward curves A and B, the curve A commencing at or near the water-line and the curve B at or near the keel. Both curves A and B meet at the bilge, and here I reversely curve the lines of the ship or boat, as shown at C, so as to form a bilge-keel in one with the side and bottom of the vessel. The finished vessel has consequently a bilge-keel on each side, as shown in Fig. 3, formed by a convexity C on the ends of two concave or inward curves A and B on the sides and bottom of the vessel. These bilge-keels C, I form

tubular and open at their ends *a a*, so as to 35 form water-ballast tanks, which fill when the vessel is launched and materially aid the inward curves A and B and bilge-keels C in maintaining the steadiness of the vessel in heavy seas. When constructing a life-boat 40 on these lines, I make it with an inner and an outer metal skin A' A' B' B and fill in the intermediate space with a material D, such as cocoanut fiber, which will prevent water from filling the space if the outer skin be damaged. 45

Having fully described my invention, what I claim, and desire to secure by Letters Patent, is—

1. A ship or boat having an open-ended bilge-keel on each side thereof formed by a 50 convexity on the ends of two concavities or inward curves on the sides and bottom of the vessel, substantially as described.

2. A life-boat comprising an open-ended bilge-keel on each side thereof formed by a 55 convexity on the ends of two concavities or inward curves on the sides and bottom of the boat, an inner and an outer metal skin, and a filling material as described between the inner and the outer skin, substantially as de- 60 scribed.

In testimony whereof I affix my signature in presence of two witnesses.

DANIEL GEORGE MARTENS.
